UNITED STATES PATENT OFFICE.

WALTER G. HOLMES, OF ROCHESTER, NEW YORK.

STERILIZER.

1,252,572.

Specification of Letters Patent.

Patented Jan. 8, 1918.

Application filed February 18, 1916. Serial No. 79,034.

To all whom it may concern:

Be it known that I, WALTER G. HOLMES, of Rochester, in the county of Monroe and State of New York, have invented a new and useful Sterilizer, fully set forth in the following specification and shown in the accompanying drawings.

The present invention relates to sterilizers and more particularly to the type in which the instruments used by surgeons, doctors, dentists, and others, are supported in a supporting and draining tray movable within a suitable hot water tank to carry such instruments to and from the water in the tank. An object of this invention is to provide a durable and compact structure having a minimum number of parts. Another object of the invention is to provide a tray adapted to be supported against movement in draining position, the supporting means preferably being employed for moving the tray toward and from draining position.

To these and other ends, the invention consists in certain parts and combinations of parts all of which will be hereinafter described, the novel features being pointed out in the appended claim.

In the drawings:

Figure 1 is a view showing the tray in side elevation, in draining position, and the hot water tank, together with its supporting frame in vertical longitudinal section;

Fig. 2 is a side view showing the supporting means for holding the tray and cover in raised positions;

Fig. 3 is a transverse vertical sectional view showing the cover and draining tray supported in raised position;

Fig. 4 is an end view of the sterilizer; and Fig. 5 is a view, similar to Fig. 3, of a modification.

Referring more particularly to the drawings, 1 indicates a tank for hot water which may be of any suitable construction. In this instance, it has a discharge 2 and is surrounded by a spaced outer wall 3 to which the foot pieces 4 are secured. An electrical, or other heater 5, is arranged on the bottom of the tank to heat the latter. For closing the hot water tank, a cover 6 is provided, hinged at one side of the tank at 7, and preferably having a chamber 8 formed therein and opening at the under side of said cover. About the chamber 8, a marginal groove 9 is formed to receive the upper edge of the hot water tank 1, and projecting

downwardly from the cover 6, when the latter is closed, are two arms 10 spaced from the end walls of the chamber 8 and provided with headed pintles 11 which project in opposite directions from the outer face of the arm. These pintles serve as pivots for the instrument-holding tray and drainer.

This instrument-holding tray and drainer preferably embodies two end walls 12 formed of sheet metal, with rounded lower edges, and connected together by a body of reticulated material 13 to provide the tray between them, the reticulated material being bent or curved longitudinally to conform to the curvature of the lower edges of the side walls. The side walls may also be provided with hand pieces or grips 14 extending above the main body of the tray, and, between these grips and the lower portions of the side walls, are formed notches 15, the inner ends of which turn upwardly at 16 to provide laterally opening bearings lying at the vertical center. Within these laterally opening bearings 16, the pintles 11 are received so that the instrument-holding and draining tray is pivotally connected to the cover and maintains an upright position on the pivots for any position to which the cover may be adjusted on its hinge 7 from its closed position to open position.

It is desirable that the cover 6 shall not be thrown so far back as to cause the drippings from the tray to fall other than in the tank 1 and, for this reason, there is provided a supporting and holding means which will support and hold the tray in a raised position above the hot water tank. This supporting and holding means preferably embodies a toggle comprising two links 17 and 18 pivoted together at 19, the links 17 also being pivoted to the cover 6, at 20, substantially at the longitudinal center of the latter, while the link 18 is pivoted at 21 to the casing 3, at one side of the vertical center of the tank 1. Preferably, the link 18 is extended at one end and provided with a hand piece 22 by which the toggle may be manually operated. A stop 23 on the link 17 cooperates with the operating extension 22 to limit the movement of the toggle in one direction, the position of this stop 23 being such that the pivot 19 moves to one side of the center line through the pivots 20 and 21, when the toggle is extended, to lock the cover and the instrument-draining and holding tray in raised positions.

In the embodiment shown in Fig. 5, the tray 12 is provided with feet 12^a which serve for supporting the tray when it is detached from the cover and also while it is within the hot water tank, the latter, for this purpose, having lugs 12^b at opposite ends for engagement by the feet 12^a. These lugs are so positioned that when the tray rests thereon, the side frames 12 become disconnected with the pintles, due to the fact that the tray engages the lugs before the cover has reached closed position.

A sterilizer constructed in accordance with this invention provides a structure which is inexpensive to manufacture and not liable to get out of order. It is unnecessary to provide any guides within the tank as the connection with the cover is direct and, when the tray is raised, it is entirely out of contact with the hot water tank so that it will not be heated by conduction and may cool off rapidly. In the embodiment shown in Figs. 1 to 4, the tray is also out of contact with the tank, when lowered, and this is also a very desirable feature as the instruments are then only heated by the hot water. The supporting toggle maintains the instrument tray in a raised position above the tank so that the tray may drain into the tank without any danger from the accidental closing of the cover.

The toggle also serves for opening the cover without injury to the operator from contact with the heated body and cover.

It will be noted that the toggle 17-18, 35 as it is straightened out or more closely approaches its dead center in the act of opening the cover, has greater and greater power, and that this takes place while it lifts the tray and its load, and continues until the 40 toggle has slightly passed a dead center where it automatically locks the cover and sustains the load.

What I claim as my invention and desire to secure by Letters Patent is:—

In a device of the kind described, the combination with a water tank and a cover hinged thereto at one side, said cover having projecting arms, of a tray pivotally hinged on said arms, and a toggle connecting said tank to said cover at points offset from its hinge, the said toggle having increasing power as it is moved toward the dead center in the act of opening said cover and raising said tray, the said toggle, in the extreme 55 open position of the cover being held in a position slightly beyond its dead center whereby the cover is locked in its open position, and the tray sustained in a raised position.

WALTER G. HOLMES.
